UNITED STATES PATENT OFFICE.

MORRIS A. LOOMIS, OF GALLION, ALABAMA.

NECKTIE STRETCHER AND SUPPORTER.

1,226,544.

Specification of Letters Patent.

Patented May 15, 1917.

Application filed June 9, 1916. Serial No. 102,722.

To all whom it may concern:

Be it known that I, MORRIS A. LOOMIS, a citizen of the United States, residing at Gallion, in the county of Hale and State of Alabama, have invented certain new and useful Improvements in Necktie Stretchers and Supporters; and I do hereby declare the following to be a full, clear, and exact description of the invention, such as will enable others skilled in the art to which it appertains to make and use the same.

This invention relates to new and useful improvements in a necktie stretcher and supporter and one of its objects is the provision of a device of this character, which shall be simple, durable and efficient, and which may be manufactured and sold at a comparatively low cost.

Another object of this invention is to provide a supporting member for supporting neckties and a clamping member for receiving the ends of the neckties whereby upon moving the clamping member from the supporting member, the neckties will be stretched to remove wrinkles and creases therefrom.

A further object of this invention is to provide rods secured to the clamping member and to the supporting member, having their ends threaded to receive a turn buckle for moving the clamping member away from the supporting member to stretch the neckties.

A still further object of this invention is to provide the clamping member constructed from a continuous piece of metal, being bent upon itself intermediate its ends and riveted together at a point adjacent the bend to form a resilient clamping arm, having its ends forked to receive a securing means for retaining the ends of the neckties between the arms of the clamping member.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a front elevation of a necktie stretcher and supporter, constructed in accordance with my invention,

Fig. 2 is a top plan view of the supporting member,

Fig. 3 is a top plan view of the clamping member,

Fig. 4 is a detail view illustrating the bent end of the supporting member to prevent neckties from slipping therefrom, and

Fig. 5 is a detail sectional view illustrating the means of securing the free end of the arm portions of the clamping member together.

Referring in detail to the drawing, the numeral 1 indicates a supporting member constructed of metal or other suitable material having each of its ends bent rearwardly upon itself to form hooks 2 and has its upper edges rounded as illustrated at 3 for supporting neckties 4 of various kinds. The hooked ends of the supporting member 1 prevent the neckties from slipping or sliding off the ends of the member 1. A suitable hook 5 is riveted or otherwise secured intermediate the ends of the supporting member 1 for supporting said member to a hook 80 or permanent object. A rod 6 is riveted or otherwise secured to the supporting member 1 intermediate its ends and depends downwardly therefrom and has its lower end screw threaded to receive a turn buckle 7. 85

A clamping member 8 constructed from a continuous piece of metal or other suitable material, is bent intermediate its ends upon itself and riveted together adjacent the bend thereof as illustrated at 9 to form a pair of 90 arms 10 and 11. The arm 11 is bent outwardly as illustrated at 12 to form a resilient arm and has its free end forked to receive a bolt 13 carried by the free end of the arm 10. The bolt 13 is screw-threaded to receive a wing nut 14 for clamping the free ends of the arms 10 and 11 together. A rod 15 is riveted or otherwise secured to the arm 10 intermediate its ends and is provided with its end screw-threaded to be received by the turn buckle 7. By rotating the buckle 7, the clamping member 8 will be moved toward and from the supporting member 1.

In operation, the resilient arm 11 of the 105 clamping member 8 is released from the arm 10 and a plurality of neckties are suspended over the supporting member 1 and have their free ends positioned between the arms 10 and 11 and by securing the free end 110 of the resilient arm 11 to the free end of the arm 10, the ends of the neckties will be effi-

ciently clamped to the clamping member 8. Then by turning or rotating the turn buckle 7, the clamping member 8 will be moved away from the supporting member 1 to stretch the neckties to remove all wrinkles and creases therefrom.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A necktie stretcher and supporter comprising a supporting member having its ends bent rearwardly upon itself to prevent neckties from slipping therefrom, said member having its upper edge rounded to support neckties, a rod secured to said member, a hook secured to said member, a turn buckle threaded to said rod, a clamping member for receiving the ends of the neckties, a rod secured to the clamping member and to the turn buckle to operatively con-

nect the clamping member to the supporting member whereby upon rotation of the turn buckle the clamping member will be moved away from the supporting member 30 to stretch the neckties.

2. A necktie stretcher and supporter comprising a supporting member, a turn buckle connected to said supporting member, a clamping member being bent rearwardly 35 upon itself intermediate its ends forming a pair of relatively spaced arms, means for securing one of said arms to the turn buckle, a rivet passed through the arms at a point adjacent the bend of the clamping member, 40 one of said arms bent outwardly from the other of said arms and provided with its end forked, and clamping means carried by the other arm to be received by the forked end of the resilient arm to clamp the ends 45 of neckties between said arms.

In testimony whereof I affix my signature in presence of two witnesses.

MORRIS A. LOOMIS.
